LOCK.

No. 399,141.

Patented Mar. 5, 1889.

UNITED STATES PATENT OFFICE.

WILLIAM SHERWOOD FISKE, OF BROOKLYN, NEW YORK, ASSIGNOR TO THE HOPKINS & DICKINSON MANUFACTURING COMPANY, OF SAME PLACE.

LOCK.

SPECIFICATION forming part of Letters Patent No. 399,141, dated March 5, 1889.

Application filed September 1, 1887. Serial No. 248,520. (No model.)

To all whom it may concern:

Be it known that I, WILLIAM SHERWOOD FISKE, a citizen of the United States, residing at Brooklyn, in the county of Kings and State 5 of New York, have invented certain new and useful Improvements in Locks; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a view of lock-case with works removed. Fig. 2 is a plan view of lock. Fig. 3 is a front view of base-plate D. Fig. 4 is a detail view of parts of lock.

The invention relates to that class of locks 20 known as "mortise-locks," wherein the mechanism within the casing can be operated upon by mechanism contained in a separate shell or cylinder lock, (for which a separate application for Letters Patent has been made under even date, Serial No. 248,519,) that may be attached to the mortise-lock after said mortise-lock has been placed in its seat, or the mortise-lock can be operated without the cylinder-lock mechanism.

Referring by letter to the accompanying drawings, A designates the main portion of the lock-case having a removable wall, said wall being secured in place by screws passed through screw-holes near the ends of said removable wall into internally-threaded lugs C, cast on the inner faces of the end walls of the main portion A, near the transverse middle lines of said end walls.

D designates the face-plate of the lock, said 40 face-plate being recessed on its inner face to receive the edges of the side plates and end plates of the lock-case. On its inner face, near each end, the face-plate D is provided with inwardly-projecting lugs E E, through which screws F are passed into internally-threaded lugs G, cast on the main portion of the lock-case and projecting inwardly from the end walls of said main portion.

The face-plate D is provided with openings 50 H and I, through which the latch-bolt and

lock-bolt, respectively hereinafter described, work when operated.

The latch-bolt comprises the head J and the flat stem K, the latter being contained within the case and branched at its inner end to form 55 the arms L and M. Said arms are provided with angularly-bent ends that project toward the removable wall of the lock-case and form the tumblers N P. The broader arm or branch, M, of the latch-bolt is slotted longitudinally at 60 Q to receive a stud, R, projecting inwardly from the enlarged portion S of a short rib, T, cast on the inner face of the fixed wall of the lock-case at the lower side of the opening W. In this opening W one end of the hub U for the 65 latch-bolt spindle works. The latch-bolt stem K is provided with a pin or stud, j', which projects toward the fixed wall of the lock-case.

j is a spring seated in a cleft-stud, 12, said 70 stud being cast integral with the fixed wall of the lock-case. The outer or free end of said spring j presses against the pin or stud j' and tends normally to press the latch-bolt outward. The latch-bolt J is also provided on its 75 lower edge with a transverse groove, s'.

t is a sector-shaped buffer hinged to the inner face of the face-plate D, and has the stud s, which travels in the transverse groove s' of the latch-bolt. This buffer t strikes the keeper 80 before the latch-bolt comes in contact therewith, and, having a rotary motion, moves the latch-bolt back or inward and relieves the lock from any shock or jar when closing the door.

A plain rib, V, is cast on the inner face of the fixed wall of the lock-case opposite to and parallel with the rib T, and upon these two parallel ribs T and V the arms L and M of the latch-bolt slide when the latch-bolt is 85 operated.

Resting upon or against the inner face of the latch-bolt is a branched slide, W', said slide being provided with a longitudinally-disposed slot, X, in its stem, said slot receiving the reduced portion of a shouldered stud, Y, said stud Y being cast integral with the fixed wall of the lock-case, projecting inwardly and at right angles thereto. The arms Y' Z of the slotted branched slide W' 100

are provided with angularly-bent ends 12. Said ends project inwardly or toward the removable wall. The hub U for the knob-spindle is provided with arms 3 and 4, the inner edges or faces of said arms being plane and engaging the angularly-bent ends 12 of the slotted branched slide W.

On its lower edge the stem K of the latch-bolt is cut away or recessed, as at 5, to receive 10 the bent end 6 of the slotted shouldered sliding fence 7. This fence 7 is provided with two slots, 7' 7'', and an arm, 7'', extending laterally and at right angles to its end, said arm engaging a stud or projection, 49², of a 15 revolving-cylinder lock. Near the latch-bolt stem and opposite the recess 5 a stud, 8', is cast on the fixed wall of the lock-case. Loosely pivoted on this stud is a slotted flanged arm or lever, 8, having a flange, 9, on 20 its inner upper edge, said flange serving as a lock or stop for the latch-bolt stem when the latter is projected. The slotted flanged lever is also provided with a slot, 10, near its free end, said slot being inclined at an angle to 25 the parallel edges of said lever. The lever 8 rests upon the inner face of the fixed wall of the lock-case.

A double-armed lever, 11, is secured upon the cleft-stud 12. The head of said stud 30 forms the seat or fastening-point for one end 35 of a spring, 14, which forces the branched slide W' outward by pressing against a pin or stud, 15, near the slot X. The inner or longer arm of the lever 11 is provided with a pin, 16, which projects into the inclined slot 10 of the lever 8. The short arm of the lever 11 is provided with an elliptical pin, 19, on its outer end. P is the lock-bolt, having the stem 18, provided with the longitudinal slot 40 33 to receive a stud 30 on the boss 31, cast integral with the fixed wall of the lock-case. This stud 30 engages either one of the rectangular notches 28 29 on the lower edge of the arm 24 of the angle-lever 25, as the case 45 may require—that is, it engages the notch 28 when the lock-bolt is projected and the notch 29 when the lock-bolt is retracted.

23' is a curved recess on the upper edge of the lock-bolt stem, in which the elliptical pin 50 19 on the lever 11 seats itself when the lock-bolt is projected.

m is a rectangular notch on the upper edge of the lock-bolt stem. The lock-bolt stem is also provided with the lugs m², placed at each 55 side of the notch m on the outer face of said lock-bolt stem for a purpose hereinafter explained.

O² is a rectangular notch on the inner lower edge of the lock-bolt stem, designed to engage 60 the projecting lug 49² of the cylinder-lock case when said cylinder-lock is operated.

44 is a slide let into the opening 42' of the fixed wall of the lock-case.

65 The lock-bolt stem has two pins or studs, 8²—one on its upper edge and one on its lower edge—projecting toward the removable wall of

the lock-case. Said pins engage the slots 7' 7'' of the fence 7.

18' is a cleft-stud secured to the stem of the 70 lock-bolt, providing a seat for a flat spring, 18², the outer or free end of which engages a lug, 18³, on the outer edge of the fence, said spring forcing the bent end 6 of the fence 7 into the recess 5 on the latch-bolt stem when 75 the lock is operated upon by the revolving-cylinder lock.

When the lock-bolt is operated by a spindle in the squared opening of the hub 32, the fence 7 is dispensed with.

Upon the inner face of the stem of the lock-bolt 18 is pivoted a lever, 20, on the upper stud, 8², said lever being provided at its outer end with a rounded dog, 21, which enters a curved notch, 22, at the junction of the long 85 and short arms 23 and 24 of an angle-lever, 25. Angle-lever 25 is pivoted on a pin or a stud, 27, entering a perforation, 26, in the lock-bolt stem immediately in the rear of the shoulder or head P of the lock-bolt.

A flat spring, 17, has one of its ends secured in a recess in the lower edge of the lever 20, the outer or free end bearing against the upper edge of the arm 24 of the angle-lever 25. This spring normally presses the angle-lever 95 25 against the stud 30 and the lever 20 against the hub 32, said hub being provided at diametrically-opposite sides with the radial arms n' n², the arms n² being located above and shorter than the arms n'.

43 is a threaded rod passing through a suitable opening in the lug 45, said lug being cast integral with the fixed wall of the lock-case and acts as a bearing for the rod 43.

44 is a slide seated in the opening 42' of 105 the fixed wall of the lock-case, said slide having a threaded opening in which one end of the rod 43 is screwed. 47 is a forked plate which engages the encircling groove 46 on the rod 43. This forked plate is designed to 110 lock the rod 43 when the cylinder-lock is seated in the opening y, and prevents the accidental removal of said cylinder-lock from its seat. This rod is designed to force the slide 44 against a shoulder on the cylinder-lock and secure it in the opening y of the said 115 wall of the mortise-lock.

The operation of the mortise-lock without the cylinder-lock and the slotted shouldered sliding fence 7 is as follows: To operate the lock-bolt when said lock-bolt is retracted, turn the armed hub 32 by a spindle placed in the squared opening in the hub till the arm n² comes in contact with the upper edge of the lever 20, which it does before the arm n' 120 comes in contact with the lugs m² on the sides of the rectangular opening m'. By continuing to turn the hub the arm n² causes the rounded dog 21 on the lever 20 to press against the arm 23 of the angle-lever 25, which 125 frees the arm 24 from the pin 30 and enables the lock-bolt to be projected. When the lock-bolt arrives at the end of its travel, the spring 11' 130 forces the elliptical pin 19 on the lever 11 into

the recess 23, forcing the slotted flanged lever 8 up, and causes the flange 9 to pass back of the latch-bolt stem, thus locking said latch-bolt. Immediately after the pin 19 comes in contact 5 with the arm 23 of the angle-lever 25 the spring 17 forces the notch 28 on the arm 24 against the stud 30. To unlock the lock-bolt, turn the spindle in the opposite direction from that used in locking it. The arms n^o on 10 the hub 32 cause the rounded dog 21 of the lever 20 to bear against the upper edge of the rounded notch 22, which movement causes the arm 23 to force the elliptical pin 19 out of the recess 23, at the same time withdrawing 15 the flange 9 of the lever 8 from engagement with the latch-bolt stem. By continuing to turn the hub 32 the lock-bolt can be retracted.

Having described my invention, what I 20 claim is—

1. The combination, with the lock-case, lock-bolt and latch-bolt, and operating-cylinder, of the slotted sliding fence connecting said lock-bolt and latch-bolt and governing the movements thereof, whereby said bolts are operated simultaneously as well as independently, substantially as specified.

2. The combination, with the lock-case provided with a stud, 30, engaging a lock-bolt 30 having a spring-actuated notched angle-lever, a latch-bolt provided with a slot or guideway,

and a shouldered stud, R, on the lock-case, of a slotted sliding fence adapted to engage a recess of the latch-bolt, and a cylinder-lock mechanism for rotating the sliding fence, substantially as specified. 35

3. The combination, with the lock-case, of the slotted and notched lock-bolt, the pivoted and notched angle-lever resting against the stem of the lock-bolt, the spring-actuated lever 40 having the rounded dog engaging the notched angle-lever on the stem of the lock-bolt, the pivoted slotted lever having the flange or stop at its inner end, the latch-bolt having the slotted branched stem engaging 45 the shouldered stud on the inner one of the parallel ribs, the branched and slotted slide resting on the stem of the latch-bolt, the pivoted lever provided with pins at its ends and engaging the notched angle-lever, and the 50 pivoted lever connected with flanged and slotted stop-lever, the slotted and shouldered sliding fence, and the armed hubs for operating the latch-bolt and lock-bolt, substantially as specified. 55

In testimony whereof I affix my signature in presence of two witnesses.

WILLIAM SHERWOOD FISKE.
